United States Patent Office.

PATRICK DOYLE, OF NEWARK, NEW JERSEY.

Letters Patent No. 99,299, dated February 1, 1870.

IMPROVEMENT IN MOULDS FOR MAKING COMBINED INGOTS OF STEEL AND IRON.

The Schedule referred to in these Letters Patent and making part of the same.

To all whom it may concern:

Be it known that I, PATRICK DOYLE, of Newark, Essex county, New Jersey, have invented a new and improved "Mould for Making Combined Iron and Steel Ingots;" and I do hereby declare that the following is a full, clear, and exact description thereof, which will enable others skilled in the art to make and use the same, reference being had to the accompanying drawings, forming part of this specification.

This invention relates to improvements in moulds for making ingots of iron and steel, in a manner to dispose the one metal on one or more sides of the other, and secure a perfect union of the two; and

It consists in a vertical mould, of four or other numbers of plain sides, one or more of which may be detachable, and clamped to the others by strong bands, in which a strong, thick plate of metal is arranged to fit near one side, from top to bottom, snugly, to occupy a part of the space, when the metal, of which the greater part of the ingot is to be composed, is poured in, and to remain until the same has solidified sufficiently to retain its position, when it is withdrawn, leaving a space for the other metal, which, being poured in, unites perfectly with the first, and forms the required composition ingot.

Figure 1 represents a sectional elevation of my improved mould;

Figure 2 is a section of the same, representing one kind of metal in it, and the plate drawn out for pouring the other;

Figure 3 is a top view of fig. 1; and

Figure 4 is a top view of a mould, showing an arrangement of movable plates on two sides.

Similar letters of reference indicate corresponding parts.

A is the vertical flask or mould of metal, composed of three sides, a, permanently connected together, one side, b, detachably connected to the others, and a bottom, c.

The side b is clamped against the others by strong bands d, so that it may be readily detached.

The edges of the sides against which b is clamped are bevelled slightly, so as to widen the space toward b. The latter has set-screws e passing through it.

f is a plate, sliding down in the mould in front of b, extending from top to bottom, and fitting snugly

in the space between the walls against which b is clamped, and bearing against the set-screws, which hold it against the bevelled faces of the sides a, or wedges may be inserted from the top, instead of the set-screws.

The iron or steel, as may be required, is poured into the space bounded by the sides a and plate f, and allowed to stand until solid enough to retain its position after the plate f is removed; the set-screws e are then slackened away from f, to free it, so that it may be drawn out; the other kind of metal (steel or iron, as the case may be,) is then immediately poured in, and permanently unites with that already in.

g, fig. 2, represents a quantity of metal in the mould, ready for the reception of that which is to be united with it, the plate f being removed.

In this way, I am enabled to make ingots, composed of steel on one side of iron, for working down to any special shapes, for articles such as skate and sleigh-runners, cutlery, &c., requiring to be of steel in one part, and iron in another.

I may also, by means of moulds such as represented in fig. 4, apply, in like manner, the steel to two sides of the iron, or the central part may be steel, and the two sides iron, or the arrangement may be such as to apply the one metal to three or even four sides of the other. In this case, the two opposite plates f, as in fig. 4, would be bevelled near the edges, for the release of other plates to be arranged between them, as shown in dotted lines h.

The sides b need not necessarily be made detachable, but, for the more ready discharge of the ingot, I prefer it.

Having thus described my invention,

I claim as new, and desire to secure by Letters Patent—

The combination, with the plain-sided mould a b c, whether having one or more of the sides b detachably connected or not, of one or more plates, f, arranged for operation substantially as specified.

The above specification of my invention, signed by me, this 17th day of December, 1869.

PATRICK DOYLE.
